UNITED STATES PATENT OFFICE.

WALTER H. HART AND DAVID GOULD, OF NEW BRITAIN, CONNECTICUT, ASSIGNEES TO THE STANLEY WORKS, OF NEW BRITAIN, CONNECTICUT, A CORPORATION OF CONNECTICUT.

FOLDING RULE.

Application filed September 12, 1921. Serial No. 500,162.

To all whom it may concern:

Be it known that we, WALTER H. HART and DAVID GOULD, citizens of the United States, and residents of New Britain, county 5 of Hartford, State of Connecticut, have invented certain new and useful Improvements in Folding Rules, of which the following is a specification.

The present invention relates to folding 10 rules made up of rule sections formed of thin strips of metal and pivoted together at their overlapping ends.

The aim of the invention is to provide a very simple device of this sort wherein the 15 rule sections may be firmly maintained in proper alinement and endwise movement of the sections, in the event wear occurs at the pivotal connections of the sections, is prevented.

20 In the accompanying drawing, wherein we have shown for illustrative purposes one embodiment which the invention may take,

Fig. 1 is a top plan view showing two sections of the rule in extended relation,

25 Fig. 2 is a view looking at the underside of three sections in extended relation, the central portion of the intermediate section being broken away,

Fig. 3 is a longitudinal sectional view 30 taken on line 3—3 of Fig. 1,

Figs. 4 and 5 are section views respectively taken on lines 4—4 and 5—5 of Fig. 1.

Referring to the drawing in detail, *a*, *a'*, *a''*, denote rule sections each comprising a 35 relatively thin strip of resilient metal, such as thin flexible steel; *b*, *b*, denote rivets pivotally connecting together the overlapping ends of contiguous sections; and *c*, *c*, denote springs for holding contiguous sections in frictional engagement with each 40 other.

In the present illustrative disclosure, each section is provided along its longitudinal center or medial line with a stiffening corrugation 11 which preferably is of increased width adjacent its ends thus providing in one face of each section pockets 12 and in the opposite face projections 13. The projections of contiguous sections correspond in 45 shape and the rivets *b* are located centrally of these projections so that the projection at the end of one section may nest in the pocket provided by the projection of the overlapping contiguous section, when the sections 50 are in either extended or folded up relations.

The springs *c*, which may comprise bowed strips of steel, are positioned in the exposed pockets 12 of the sections. The rivet extends through alined perforations in the projections and spring and is suitably headed 60 at both ends to secure the parts in frictional engagement.

It will be seen, particularly from Fig. 3, that when the projections 13 are in nesting relation the end walls or transverse shoulders 14 of the pockets and projections interengage and thereby effectively prevent relative endwise or longitudinal movement of the sections in the event the rivets or the edges of the perforations receiving the same 70 become worn due to repeated turning movement of the sections. Thus the sections are effectively maintained in such relation that the original length of the rule is not disturbed nor affected by wear at the pivotal 75 connections. When the sections are turned relatively to one another, the springs will flex permitting the corrugations and projections to ride into and out of nesting relation, while at the same time holding the sections 80 in frictional engagement.

It is of course obvious that our invention is susceptible of various modifications and changes which are within the spirit of the invention without departing from the scope 85 of the following claims it being understood that the present disclosure is by way of illustration only and it is not to be taken as restrictive of our conception.

What we claim is:

1. In an all-metal folding rule, a pair of rule sections having overlapping ends, each comprising a thin strip of metal having a corrugation extending substantially throughout its length, a separate spring holding said 95 sections in frictional engagement, and a pivot member pivotally connecting said sections together and holding said spring in place.

2. In an all-metal folding rule, a pair of rule sections having overlapping ends, each comprising a thin strip of metal having a corrugation extending substantially throughout its length, a separate spring in the corrugation of one section and holding said sections in frictional engagement, and a rivet extending through aligned perforations in said sections and spring and headed at each end to secure said parts together.

3. In an all-metal folding rule, a pair of

- rule sections having overlapping ends, each section comprising a thin strip of metal, said sections having projections struck up out of the plane thereof and adapted to nest 5 one within the other when the sections are in alignment, a separate spring positioned in the pocket provided by one of said projections, and a pivot member connecting said sections and spring together.
- 10 4. In an all-metal folding rule, a pair of rule sections each comprising a thin strip of resilient metal provided with a longitudinally extending stiffening corrugation, one of said members having a pocket in its exposed face, a separate spring positioned in said pocket for holding said sections in frictional engagement, and a rivet connecting said sections and spring together.
- 15 5. In an all-metal folding rule, rule sections each comprising a thin strip of resilient metal, the overlapping end of one section having a struck-up projection forming a pocket, and the overlapped end of the contiguous section having a corresponding projection adapted to nest in said pocket with the end walls or shoulders of said pocket and corresponding projection in engagement with each other, a separate spring in the exposed pocket provided by the projection in 20 the overlapped section, and a rivet connect- 25
- ing said sections and spring and disposed centrally of said projections.
6. In an all-metal folding rule, rule sections each comprising a thin strip of resilient metal provided with a longitudinal stiffening corrugation, the corrugations at the overlapping ends of contiguous sections being of increased width to form a pocket in one section and a corresponding projection in the contiguous section adapted to nest in 30 said pocket with the lateral shoulders at the ends of said pocket and projection in engagement with each other, and a rivet centrally disposed of said pocket and projection. 35
7. In an all-metal folding rule, rule sections each comprising a thin strip of resilient metal provided with a longitudinal stiffening corrugation, the corrugations at the overlapping ends of contiguous sections being of increased width to form corresponding projections adapted to nest one within the other, a separate spring disposed in the pocket provided by one of said projections, and a rivet disposed centrally of said 40 projections and securing said sections and spring together. 45
